JULIAN H. FAW, OF MORSEMORE, NEW JERSEY, ASSIGNOR TO J. H. FAW, INC., OF NEW YORK, N. Y., A CORPORATION OF NEW YORK.

ELECTRICAL LAMP-SOCKET AND SWITCH.

1,185,646.

Specification of Letters Patent.

Patented June 6, 1916.

Application filed July 27, 1914. Serial No. 853,291.

To all whom it may concern:

Be it known that I, JULIAN H. FAW, a citizen of the United States, and a resident of Morsemere, in the county of Bergen and 5 State of New Jersey, have invented certain new and useful Improvements in a Combined Electrical Lamp-Socket and Switch, of which the following, taken in connection with the accompanying sheet of drawings, is 10 a full, clear, and concise description thereof.

My invention relates particularly to electrical lamp sockets adapted to accommodate electric lamps capable of being detachably connected therewith, and has for its object 15 the provision of a self-contained switch forming a part thereof which provides for the convenient control of the lighting circuit. To the accomplishment of this object, I provide a two-part casing, the parts insulated one from the other, but adapted to be brought into electrical connection through 20 the instrumentality of an annular ring, which is movably mounted upon one part of the casing, but adapted to be brought into 25 connection with the other part of the casing, thus bridging the two and forming a conductive part for the current. It will be understood that the socket is one wherein the shell or casing forms part of the circuit, and, 30 therefore, must coöperate with a lamp, which is provided with a casing forming one of its terminals. The other terminal of the lamp being centrally disposed of the lamp, coöperates with a centrally located terminal of 35 the socket so as to form a complete circuit when the conducting wires are connected to the respective terminal parts of the socket.

Referring to the accompanying drawing, Figure 1 is a view in side elevation of a lamp 40 socket embodying my invention. Fig. 2 is a cross-sectional view taken on line *a—a* of Fig. 1 with the switch open. Fig. 3 is a fragmentary detail, similar to Fig. 2 excepting that the switch is shown closed.

45 In detail, the lamp socket comprises a shell of two-part construction indicated by the numerals 1 and 2. These are mounted upon a plug of insulating material 3, the part 1 being held in position by a suitable screw 4 and part 2 by a suitable screw 5. Preferably 50 molded within the center of the insulated plug is a tube 6, within which the resiliently mounted spring plunger 7 is held and normally pressed outwardly under the tension 55 of the spring 8. This plunger engages and

forms electrical contact with the centrally located terminal 9 of the lamp 10. The lower end of the tube 6 receives the end of a flexible conductor, which is held therein by means of the screw 11. The screw 11 60 serves the dual purpose of holding the conductor in electrical engagement with the tube 12, and also holding the part 2 of the casing upon the insulated plug 3. In addition to this it serves as a conductive path for 65 the current.

It will be understood that the lamp 10 is provided with a plug end having a conductor shell 13, which serves as one terminal of the lamp. This plug end is provided 70 with pins 14 diametrically opposite one another which coöperate with slots 15 of the part 1 of the socket, so that the lamp can be brought into coöperative relationship therewith. The circuit then is through the 75 tube 6, plunger electrode 7, lamp terminal 9, filament of the lamp, one end of which is grounded or in electrical connection with the casing 13 and part 1 of the lamp socket. Now in order to complete the circuit, the 80 screw threaded knurled ring 16 is provided and is mounted upon the screw threaded end 17 of the part 2 of the socket. This knurled ring is rotated until it engages the chamfered end of the part 1 of the lamp socket 85 as shown in Fig. 3. This completes the circuit so that the current will flow through the ring 16, part 2 of the lamp socket, screw 5, tube 12 and the other flexible conductor to the battery or other source of electrical 90 energy (not shown).

While I have illustrated one specific form or embodiment of my invention, I would have it understood that I do not wish to be restricted to the specific details of construction, as these may be altered and departed from without departing from the spirit and scope of my invention as defined by the following claims.

Having thus described my invention, what 100 I claim as new herein and desire to secure by Letters Patent is:

1. A combined electric lamp socket and switch comprising a cylindrical shell of two-part construction, an insulating plug within 105 said shell and supporting said two parts thereof in separated and insulated position, said insulating plug carrying a conductor adapted to engage one terminal of a lamp when said lamp is inserted in one part of the 110

- shell, and a rotating member adapted to be brought into engagement with both parts of the shell to complete an electrical circuit through the lamp.
5. 2. A combined lamp-receiving socket and switch comprising a socket adapted to detachably support a lamp and form electrical connection with one terminal thereof, and an insulating plug supported within said
- 10 socket provided with a conductor terminal adapted to contact with the other terminal of the lamp, means carried by said insulating plug for connecting a pair of flexible conductors thereto, an exterior conductor
- 15 member carried by said plug and in electrical connection with one of the flexible conductor members when the same is fastened to the insulating plug, and a movable conductor member adapted to connect said exterior conductor member with the lamp-receiving socket to complete the circuit through the lamp.
- 20 3. An electric lamp socket comprising a plug of insulating material, provided with fastening means for flexible conductors, and a centrally located plunger conductor for engagement with the central electrode of a lamp, of a two-part shell mounted upon the insulated plug and electrically separated
- 25 from each other, one part of the shell being provided with means adapted to accommodate a lamp and form electrical connection with one terminal thereof, and a conducting member mounted upon one part of the shell
- 30 adapted to be brought into contact with the other part of the shell to complete a conductive path through the lamp.
- 35
4. A combined electric lamp casing and switch, comprising a cylindrical shell, including two shell members of conducting material insulated from each other, one member being formed with a lamp-receiving orifice to accommodate a lamp removably fitted therein and forming electrical connection with one terminal thereof, the other member forming part of the electrical circuit, and a movable conductor member co-operatively associated with both members of the casing and operating to establish a circuit through the same to illuminate the lamp.
5. A combined electric lamp casing and switch, comprising a cylindrical shell, including two shell members of conducting material insulated from each other, one member being formed with a lamp-receiving orifice to accommodate a lamp removably fitted therein and forming electrical connection with one terminal thereof, the other member forming part of the electrical circuit, a terminal within the casing but insulated therefrom, adapted to contact with the other terminal of the lamp, and a movable conductor member co-operatively associated with both members of the casing and operating to establish a circuit through the same to illuminate the lamp.

In witness whereof I have hereunto set my hand in the presence of two subscribing witnesses.

JULIAN H. FAW.
